UNITED STATES PATENT OFFICE.

GEORGE VEETMEIER, OF MILWAUKEE, WISCONSIN.

DESIGN FOR A LAMP.

Application filed October 8, 1925. Serial No. 15,066. Term of patent 7 years.

To all whom it may concern:

Be it known that I, GEORGE VEETMEIER, a citizen of the United States, residing at Milwaukee, in the county of Milwaukee and State of Wisconsin, have invented a new, original, and ornamental Design for a Lamp, of which the following is a specification, reference being had to the accompanying drawing, forming a part thereof.

I claim:

The ornamental design for a lamp as shown.

GEORGE VEETMEIER.
